BATHROOM DRYING FIXTURE

Marvin Hoodis, 223 Lenox Road, Brooklyn, N.Y.

Filed Apr. 12, 1965, Ser. No. 84,730

Term of patent 14 years

(Cl. D49—1)

FIG. 2 is a front elevational view thereof,

FIG. 3 is an end elevational view thereof.

The broken lines shown in FIG. 1 are for illustrative purposes only.

I claim:

The ornamental design for a bathroom drying fixture, substantially as shown and described.
